(57) **CLAIM**

The ornamental design for a rotatable floor lamp, as shown and described.

DESCRIPTION

FIG. 1 is a top, front and right side perspective view of a rotatable floor lamp showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a top, front and right side perspective view showing the rotatable floor lamp in an alternate state of use; and,

FIG. 9 is an enlarged view of portion 9 in FIG. 1. The broken lines shown in the drawing are for the purpose of illustrating the boundaries of the enlarged fragment shown in FIGS. 1 and 9 and form no part of the claimed design.
